[57] **CLAIM**

The ornamental design for a web for a baseball glove, as shown and described.

DESCRIPTION

FIG. 1 is a front perspective view of a web for a baseball glove showing my new design;

FIG. 2 is a rear perspective view thereof.

The portion of the baseball glove shown in broken lines in FIGS. 1 and 2 is for illustrative purposes only and forms no part of the claimed design.

FIG.1

FIG. 2
